UNITED STATES PATENT OFFICE.

LEWIS G. ROWAND, OF BROOKLYN, NEW YORK, ASSIGNOR TO THE NEW JERSEY ZINC COMPANY, OF NEW YORK, N. Y., A CORPORATION OF NEW JERSEY.

INCLINED SCREEN.

1,294,309.

Specification of Letters Patent.

Patented Feb. 11, 1919.

Application filed March 23, 1918. Serial No. 224,138.

To all whom it may concern:

Be it known that I, LEWIS G. ROWAND, a citizen of the United States, residing at Sea Gate, borough of Brooklyn, in the county of 5 Kings, city and State of New York, have invented certain new and useful Improvements in Inclined Screens; and I do hereby declare the following to be a full, clear, and exact description of the invention, such as 10 will enable others skilled in the art to which it appertains to make and use the same.

The present invention relates to improvements in inclined screens especially adapted for the screening of ores. Inclined 15 screens for this purpose have heretofore been constructed of a number of separate screen sections fixed upon an inclined frame, and having screening surfaces of suitable mesh to cause successive removal of 20 particles of increasing size as the ore falls over the sections. The screens are placed within an inclosed chamber provided with pockets to receive the screenings, and doors are provided in order to permit access to 25 the chamber. Since the screens are of considerable height, the doors carry steps or stair rounds upon which an operator may ascend to clean out any of the screen sections which may have become clogged in 30 service, and also to reach the gateway for controlling the supply of ore to the apparatus, this gateway being located at the upper end of the apparatus.

Apparatus of the type referred to above 35 possesses certain disadvantages, inasmuch as the screen sections are fixed in place so that it is a somewhat difficult matter to properly clean them, as the particles become wedged in the meshes of the screens and the operator 40 cannot reach the under surface of the screen to brush out these wedged particles. Furthermore, since the supply gateway is located at the top of the apparatus, it is necessary for the operator to ascend the apparatus every time he wishes to stop or start 45 the flow of ore, or to change the size of the supply opening. In practice, it is frequently desirable to change the inclination of the screening surfaces, but in apparatus as 50 usually constructed, the screening surfaces are fixed in place so that they cannot be altered without a considerable reorganization of the apparatus.

The present invention seeks to overcome 55 the disadvantages of prior apparatus of the

general type described above by providing an inclined screen, especially adapted for the screening of ores, in which each screen section is adjustably mounted so that the angle of inclination of the screening surface 60 may be altered within certain limits, and in which this screening surface is hinged to the frame of the section, so that it may be tipped to permit it to be cleaned from both sides. Another improvement in the apparatus of the present invention consists in 65 connecting the gateway for controlling the supply of ore to the screens to an operating rod extending the entire length of the apparatus, and serving in addition as a hand rail 70 for use by an operator in ascending or descending over the screen. The operating rod is provided at intervals with handles by which it may be manipulated by an operator to control the gateway from any point of the 75 apparatus, thus resulting in a material saving of the operator's time over the former apparatus in which the operator is obliged to ascend to the top every time he wishes to manipulate the gateway. The mechanism 80 for operating the gateway is also provided with devices by means of which the size of the ore discharge opening may be regulated.

Other objects and advantages of the present invention will appear more clearly from 85 a description of a preferred embodiment thereof as illustrated in the accompanying drawings in which Figure 1 is a side elevation principally in section; Fig. 2 is a plan view with parts in section along the line 90 2-2 of Fig. 1; Fig. 3 is an enlarged view of a portion of Fig. 1; Fig. 4 is a transverse section along the line 4-4 of Fig. 3; Fig. 5 is a transverse section along the line 5-5 95 of Fig. 1 and Fig. 6 is a transverse section through the ore supply hopper along the line 6-6 of Fig. 1.

Referring to the drawings in which similar reference characters denote similar parts throughout the several views, the frame of 100 the apparatus is composed of side members or girders 10 set at the proper inclination, which in the embodiment here shown is approximately 60° to the horizontal. At their lower ends, the girders are fastened between 105 angle bars 11 forming the base of the apparatus and connected to other angle bars 12 attached to the floor. Between the angle bars 11 is a divider 13 which serves to brace these bars and to separate the base of the 110

apparatus into two compartments, beneath which are hoppers 14 leading to suitable conveyors. One of the hoppers receives the particles rejected from the screen while the other receives those that pass through the lowermost sections of the screen.

The rear edges of the girders 10 are connected by plates 15, and if the structure is of considerable length it should then be supported at one or more points by transverse girders 16 connected to suitable supports at the sides of the apparatus. At the upper end of the apparatus is a transverse frame 17, which serves as a support for the feed hopper 18 into which the ore is supplied in any convenient manner. The lower end of the feed hopper is closed by a gate 19 pivoted as shown most clearly in Fig. 6 to lugs 20 projecting from the wall of the hopper. A rod 21 has one end connected to the gate, and its other end is connected to an arm 22 mounted on the upper end of an operating rod 23, which passes through a bearing in a T 24 attached to the outer end of a post 25 set in a floor flange 26 mounted upon a cross bar 27, which extends across the front of the apparatus and is attached to the girders 10 by angle irons 28. The lower end of the operating rod 23 passes through a bearing member 29 on the end of another post 25 similar to, and attached in the same manner as the post at the top of the apparatus. In order to take up the weight of the operating rod 23, a spring 30 surrounds the lower end of the rod between the upper face of the bearing member 29 and a collar 31 which may be adjustably attached to the rod 23. A number of operating handles 32 are attached to the rod 23, and these handles should preferably be arranged so that they may be adjusted longitudinally of the rod to bring them into position where they may be conveniently reached by an operator from various points of the apparatus. In connection with the above described mechanism for operating the gate 19, there is provided in the T 24 a fixed stop 33, and an adjustable stop 34 in the form of a plate having a slot through which passes a clamping bolt 35 threaded into the T. The arm 22 is provided with a reduced end as at 36 adapted to engage either of the stops 33 or 34 to limit the movement of the arm and consequently the extent of opening of the gateway.

The ore screening devices of the apparatus comprises a plurality of pockets and screen sections arranged between the girders 10, and of the requisite number necessary to produce the desired successive screening of the ore during its passage through the apparatus. The upper pocket 40 which lies just below the discharge end of the feed hopper 18 has end portions 41 attached to the girders 10 by bolts, and a transverse

shelf portion 42 to which is attached a wearing plate 43, which is constructed of hard steel and is provided with slots through which pass bolts 44 by means of which the position of the wearing plate upon the shelf of the pocket may be adjusted. Each of the other pockets 45 has side portions by which it is attached to the girders 10, and has a rear shelf 46 similar to the shelf of the pocket 40, and having attached thereto a steel wearing plate 47. These pockets are also provided with front shelves 48 to which steel wearing plates 49 similar to the wearing plates 47 are adjustably attached.

Each of the screen sections of the apparatus comprises a screen 50, preferably formed of a metal plate perforated with narrow slots of a width suitable to permit the passage of ore particles of a certain size, the screens having the narrowest slots being at the top of the apparatus. Each screen plate is mounted in a rectangular frame 51, and each frame is attached at its lower end by hinges 52 to a support 53. The supports are bolted to inclined members 54 extending between the ends of the pockets 45, and preferably formed as continuations of the rear shelves 46 of these pockets. Slots are provided in either or both the members 54 and the supports 53 to permit the angle of inclination of the screen frames to be altered within certain limits. When the screen frames are in normal position, their upper ends rest on ledges formed by projections 55 at the bottom of the rear shelves of the pockets. When in open position the ends of the frames rest upon the cross bars 27 at the front of the apparatus. While the screen frames extend substantially from one girder to the other, there may be narrow spaces at their ends through which un-screened ore might fall. In order to fill these spaces, wooden strips 56 placed on and attached to the girders 10 are provided. At their upper ends, these strips are fitted beneath the rear shelves 46 of the pockets, and at their lower ends they fit against the members 54, or closely adjacent the supports 53 in case the latter extend completely to the girders. The lowermost screen frame has its support 53 adjustably attached to the inclined face 57 of a triangular bracket 58 which is attached to the base frame of the apparatus.

For the purpose of collecting the particles of ore after they have passed through the screens, there is provided a series of pockets formed by means of liners 60 which are bolted to the girders 10 and are provided with outwardly extending lugs 61 forming slots within which are inserted transverse choke bars 62 forming the bottom of each of the pockets. The pockets which receive screenings of one size should preferably be provided with a chute 63 through which

these screenings may be discharged, and there should be as many of these chutes as there are screens of different mesh, excepting at the bottom of the apparatus where 5 the last screenings fall into one of the hoppers 14. At the points where the chutes are led off, the choke bars should be extended as indicated at 62' in Fig. 1, in order to prevent any screenings from falling into 10 lower pockets.

As has been previously stated, the posts 25 are mounted upon transverse members 27 which are attached to the girders 10 by angle irons 28, but in addition to the transverse 15 members to which the posts are attached there are a number of others throughout the length of the apparatus. These transverse members serve as supports to which the covers of the apparatus are attached, and also 20 serve as abutments for the lower ends of the covers, as well as for the screen frames when the latter are in open position. Each of the covers comprises a frame work 65 hinged as at 66 to one of the transverse members 27, and having its lower end formed to 25 rest upon the upper edge of the next lowest member 27. Each cover is provided with brackets 67 and between these brackets are rounds 68 which form steps. Pivoted to 30 each cover are latches 68', which, as shown most clearly in Fig. 3 are adapted to fit over the stair rounds of the cover immediately above to hold the cover open. At the top of the apparatus is a hinged cover 69 which 35 is turned into the dotted line position permits access to the gate mechanism associated with the feed hopper. This cover is provided with a staple or hook 70 to which the latch of the upper door may be attached. 40 In the operation of the apparatus described above the ore is supplied to the feed hopper 18, and when the gate 19 is opened the ore drops into the upper pocket 40 and when a pile of ore has accumulated on shelf 45 it falls over the edge of the wearing plate of this pocket and drops onto the screening surface. Particles of a size to pass through this screen will fall into the receiving pockets at the rear of the apparatus, while the 50 over size particles will fall upon the front shelf 48 of the pocket 45 and when sufficient material has accumulated on this shelf, it will fall off over the wearing plate 49 onto the rear shelf of the same pocket and from 55 the latter, it will pass over the wearing plate 47 onto the screening surface immediately below. After the pockets become filled the ore will fall upon ore and thus have less tendency to abrade the metal of which the 60 pockets are formed. The wearing plates being of hard steel are not so readily abraded by the ore falling over them. In the preferred embodiment, this screening surface is supposed to be of the same mesh 65 as the first one, and thus will screen out

particles which failed to go through the first screen. These particles will fall into the receiving pockets and as the latter become sufficiently filled, the material will flow over the choke bars, and finally pass into the 70 chute 63. The ore will continue its course throughout the entire length of the apparatus, particles of gradually increasing size being successively removed and finally the particles that are too large to pass through 75 any of the screens will fall onto the horizontal portion of the bracket 58, and pass over the edge of the latter into the forward hopper 14. The particles of largest size which pass through the lowermost screens 80 will be collected in the pockets at the bottom of the apparatus and flow over the choke bars into the rear hopper 14.

In apparatus of this character, it is necessary to clean the screening surfaces at intervals, and in order to do this in the present case, the operator ascends to the screen sections to be cleaned, and after stopping the feed of ore, lifts the cover of the section to be cleaned, and swings the screen into its 85 open position. By means of suitable brushes or cleaning implements, he may then clean both sides of the screen, so that any particles which have become wedged in the meshes of the screen will be dislodged by one or the 90 other of the cleaning operations. If at any time, while the operator is upon the apparatus he desires to start or stop the flow of ore therethrough, he may manipulate the gate 19 by rotating the rod 23 by means of the 100 nearest handle 32. At the same time, he may use the rod 23 for a hand rail while traveling over the apparatus. By means of the adjustable stop 34 on the T 24 on the upper end of the apparatus, the size of the 105 ore feed opening may be altered to suit the particular ore that is being screened and after the stop has been set for an opening of a certain size, the same size of opening will always be presented whenever the gate 110 is manipulated. The inclination of the screening surfaces may be altered within certain limits, preferably between 35° and 45° to the horizontal, by means of the bolt and slot connections of the supports 53, and the 115 operator may effect this adjustment by reaching through the doorways on the front of the apparatus.

With the apparatus described above, the screening surfaces may be thoroughly 120 cleaned, they may also be set at the proper inclination for producing the most effective screening, and ore may be supplied at the rate adapted for best results. A considerable saving of the operator's time may be 125 effected by the provision of the operating rod, which may be manipulated from any part of the apparatus to control the operation of the gate, and in fact, the gate may even be manipulated from the ground by 130

providing a handle 32 which may be reached by an operator at the base of the apparatus.

I claim:

1. In ore screening apparatus provided with an inclined frame and ore pockets mounted on the frame, the combination of a plurality of inclined screens between the pockets, each of said screens being pivoted at one end to a pocket and supported at the other end upon an adjacent pocket.

2. In ore screening apparatus provided with an inclined frame and ore pockets mounted on the frame, the combination of a plurality of inclined screens between the pockets, each of said screens being pivoted at its lower end to the top of a pocket and having its upper end supported upon the bottom of an adjacent pocket.

3. In ore screening apparatus provided with an inclined frame and ore pockets mounted on the frame, the combination of supports adjustably attached to the upper ends of the pockets, and inclined screens each having one end pivoted to one of said supports and the other end resting upon the bottom of an adjacent pocket.

4. In ore screening apparatus provided with an inclined frame and ore pockets mounted on the frame, the combination of supports adjustably attached to the upper ends of the pockets, and inclined screens each having its lower end pivoted to one of said supports and its upper end resting upon the bottom of an adjacent pocket.

5. In ore screening apparatus provided with an inclined frame and ore pockets mounted on the frame, the combination of supports adjustably attached to the upper ends of the pockets, inclined screen frames, each having one end pivoted to one of said supports and the other end resting upon the bottom of an adjacent pocket, and a screen surface mounted on each of the frames.

6. In ore screening apparatus provided with a frame consisting of inclined spaced members and pockets mounted between the members, the combination of a plurality of inclined screens between the pockets, each of said screens being pivoted at one end to a pocket and supported at the other end, when in operative position, upon an adjacent pocket, and transverse supports mounted between the frame members at the forward edges thereof and upon which said screens may rest when swung into position to be cleaned.

7. In ore screening apparatus provided with a frame consisting of inclined spaced members, the combination of a plurality of inclined screens between the pockets, each of said screens being pivoted at one end to a pocket and supported at the other end, when in operative position, upon an adjacent pocket, transverse supports mounted be-

tween the frame members at the forward edges thereof and upon which said screens may rest when swung into position to be cleaned, and doors pivoted to said transverse supports and resting upon the forward edges of the inclined members, through which access may be obtained to the screens.

8. In ore screening apparatus provided with an inclined frame, having at its upper end an ore-feed hopper provided with a gate, the combination of an operating rod rotatably mounted upon the frame and extending from top to bottom thereof, handles adjustably mounted upon the rod, and an operating connection between the rod and the gate.

9. In ore screening apparatus provided with an inclined frame having at its upper end an ore-feed hopper provided with a gate, the combination of means whereby said gate may be operated from any part of the apparatus, said means comprising an operating rod rotatably mounted upon the frame in substantially parallel relation thereto, and an operating connection between the rod and the gate.

10. In ore screening apparatus provided with an inclined frame having at its upper end an ore-feed hopper provided with a gate, the combination of posts mounted upon the forward edge of the frame, a rod mounted in said posts, a spring support for the lower end of the rod, an arm attached to the upper end of the rod, a connection between the arm and the gate, and actuating handles adjustably mounted on the rod.

11. In ore screening apparatus provided with an inclined frame having at its upper end an ore-feed hopper provided with a gate, the combination of posts mounted upon the forward edge of the frame, a rod rotatably mounted in said posts in convenient position to be used as a hand-rail, handles adjustably mounted on the rod and by means of which the rod may be rotated, an arm attached to the upper end of the rod and a connection between the arm and the gate.

12. In ore screening apparatus provided with an inclined frame having at its upper end an ore-feed hopper provided with a gate, the combination of posts mounted upon the forward edge of the frame, bearings upon the outer ends of the posts, a rod rotatably mounted in the bearings, an arm attached to the upper end of the rod, stops mounted on the bearing of the topmost post for limiting the moving of the arm, a connection between the arm and the gate, and operating handles adjustably mounted on the rod.

13. In ore screening apparatus provided with an inclined frame having at its upper end an ore-feed hopper provided with a gate, the combination of posts mounted upon the forward edge of the frame, bearing members upon the outer ends of the posts, a rod

- rotatably mounted in the bearing members, an arm attached to the upper end of the rod, a fixed stop and an adjustable stop mounted upon the bearing member of the topmost 5 post and adapted to be engaged by one end of the arm to limit movement thereof, a connection between the other end of the arm and the gate, and operating handles adjustably mounted on the rod.
- 10 14. In ore screening apparatus provided with an inclined frame having ore pockets mounted therein and an ore feed hopper at the upper end of the frame provided with a gate for controlling the feed of ore to the apparatus, the combination of inclined screens 15 each having one end pivoted to a pocket and the other end resting upon an adjacent pocket, bars attached to the front of the frame upon which the screens may rest when 20 swung from normal position, said bars also forming steps along the front of the frame, and means whereby an operator may control the gate from the vicinity of any of the screens, said means comprising a rod extend- ing along the frame, an arm on the upper end 25 of the rod and a connection between the arm and the gate, said rod also serving as a hand-rail for an operator when upon the steps.
15. In ore screening apparatus provided with an inclined frame having steps along the front face, ore pockets mounted within the frame, and an ore feed hopper and gate at the upper end of the frame, the combination of a plurality of inclined screens each 30 of which is pivotally attached to a pocket so that it may be swung forwardly and supported upon a step in position to be cleaned by an operator upon the steps, and means whereby the operator may at the same time 35 control the feed of ore to the pockets and screens, said means comprising a rod extending along the frame, adjustable operating handles upon the rod and a connection between the rod and the gate. 40 45

In testimony whereof I affix my signature.

LEWIS G. ROWAND.
